UNITED STATES PATENT OFFICE.

HEINRICH PFERDMENGES, OF GIESENKIRCHEN, NEAR RHEYDT, GERMANY.

MACHINE FOR MOISTENING YARN.

Application filed December 23, 1927, Serial No. 242,248, and in Germany December 30, 1926.

This invention relates to a machine for moistening yarn in cops, hanks and the like. For this purpose machines are known in which the yarn is carried past the moistening apparatus on belt conveyors, the moisture being supplied by rotating rollers to centrifugal brushes, which spray it on to the yarn.

This invention solves the problem of enabling the quantity of moisture to be regulated, in such a manner that the weight of moisture sprayed works out at a definite percentage, known to be advantageous, of the weight of the yarn. The invention is essentially characterized by the fact that the ratio between the velocity with which the material is conveyed and the speed of revolution of the rollers that supply the moisture to the centrifugal brushes is made capable of being regulated in a special way.

20 The invention is further characterized by the fact that an adjustable bar is provided with marks which denote the nature of the spun material, the belt driving the moistening apparatus being adjustable to these marks.

25 While the marks on the adjusting rail have reference to the nature and constitution of the spun materials to be moistened, it is furthermore requisite to effect a correction according to the condition of the atmosphere in 30 the work room, which is known to be subject to great variations, this correction working out at the same percentage for all spun materials. For this purpose the driving pulleys for the moistening apparatus are of such a 35 curved form that a displacement of the adjusting bar ensures the same percentage increase or decrease of moistening for all spun materials.

40 The adjusting of the bar bearing the marks may be effected by means of a spindle provided with a toothed wheel which meshes with a second toothed wheel. The shaft of this latter toothed wheel stands at the free end in front of a scale, according to which, by 45 using a device indicating the condition of the air in the work room, or a corresponding table, the adjustment is effected.

45 The invention is diagrammatically illustrated by way of example in the accompanying drawings, wherein:

Figure 1 is a view of a belt conveyor, with moistening apparatus;

Figure 2 is a view of the drive of the roller serving for supplying the moisture; and

55 Figure 3 is a view of the change-speed gear, with mark adjustment.

On a belt conveyor *a*, Figures 1 and 2, the spun material *s* is carried through underneath the moistening apparatus. The moistening apparatus consists of a vessel *b*, which is filled 60 with liquid, and in which there revolves a roller partially immersed in the liquid, the surface of the roller therefore always being wetted with moisture. A high-speed brush roller *d* strips off the moisture carried away 65 upon the immersion roller *c*, atomizes it, and throws it on to the material *s*.

The immersion roller *c* receives its drive by means of a double-cone belt drive *k*, *k'*, with which to every position of the belt *f* there corresponds a definite speed of revolution of the roller *c*, and consequently a definite quantity of moisture delivered per unit of time. A scale *e* for the belt facilitates the adjustment. Instead of the belt drive *k*, *k'* any other 75 change-speed gear may of course be employed, such as a friction-disc or toothed-wheel gear.

According to Figure 3, the bar *l*, which is connected by bolts *i* with a bar *p*, bears marks *m*, *m* which denote the nature and constitution of the spun material. In the selected example a driving belt *q*, which is guided by a fork *n* in a slot *o* in the bar *p*, and which runs over curved driving pulleys *r*, *r'*, is adjusted to the mark *m'*. The pulleys *r*—*r'* drive the 85 belt *a*, as will be understood. By means of a positioning wheel *q'* on a spindle *q*², which is supported in bearings *t*, *t* and guided in a nut *u*, the bar *l* admits of being shifted relatively to the remaining machine parts *v*, *v'*, 90 which are stationary. Upon the spindle *q*² is mounted fast a toothed wheel *w*, which meshes with a toothed wheel *x*. The shaft of the wheel *x* carries at the free end a pointer *y*, standing in front of a scale, which may be 95 fitted to the wheel *x*.

So long as spun material of the same kind and quality is to be treated the belt fork *n* may be fixed in the slot *o* in the bar *p*, so that merely by adjusting the wheel in accordance 100 with the condition of the air in the work room the belt *q* is guided into its appropriate position.

What I claim is:

1. An adjusting device for yarn-moistening machines including a centrifugal brush for scattering moisture over the yarn, a belt conveyor for carrying the yarn past said centrifugal brush, an immersion roller adapted to supply moisture to said centrifugal brush, means for driving said belt conveyor, means for driving the immersion roller, a change

speed gear for varying the ratio between the speed of the immersion roller and the speed of the belt conveyor, said change speed gear including a slotted positioning bar bearing

5 marks denoting the nature of the yarn, a driving belt, and a belt fork, slideable in the slot in the positioning bar, for shifting said belt from one mark to another.

2. An adjusting device for yarn-moistening machines including a centrifugal brush 10 for scattering moisture over the yarn, a belt conveyor for carrying the yarn past said centrifugal brush, an immersion roller adapted to supply moisture to said centrifugal brush,

15 means for driving said belt conveyor, means for driving the immersion roller, a change speed gear for varying the ratio between the speed of the immersion roller and the speed of the belt conveyor, said change speed gear

20 including a slotted positioning bar bearing marks denoting the nature of the yarn, a driving belt, a belt fork, slideable in the slot in the positioning bar, for shifting said belt from one mark to another, a spindle adapted

25 to displace the positioning bar longitudinally, a toothed wheel mounted on said spindle, a second toothed wheel meshing with said toothed wheel, a scale applied to said second toothed wheel, a shaft on which said second toothed wheel is mounted, and a pointer at the free end of said shaft, said pointer standing in front of said scale.

3. An adjusting device for yarn-moistening machines including a centrifugal brush 30 for scattering moisture over the yarn, a belt conveyor for carrying the yarn past said centrifugal brush, an immersion roller adapted to supply moisture to said centrifugal brush,

35 means for driving said belt conveyor, means for driving the immersion roller, a change speed gear for varying the ratio between the speed of the immersion roller and the speed of the belt conveyor, said change speed gear including a slotted positioning bar bearing

40 marks denoting the nature of the yarn, a pair of driving pulleys having curved surfaces, a driving belt passing round said driving pulleys, a belt fork, slideable in the slot in the positioning bar, for shifting said belt from one mark to another, the curvature of the surfaces of the driving pulleys being such

45 that a displacement of the positioning bar ensures the same percentage increases and decreases in moistening for all the spun materials corresponding to the various marks on the positioning bar, a spindle adapted to dis-

50 place the positioning bar longitudinally, a toothed wheel mounted on said spindle, a second toothed wheel meshing with said toothed wheel, a scale applied to said second toothed wheel, a shaft on which said second toothed wheel is mounted, and a pointer at the free end of said shaft, said pointer standing in front of said scale.

55 4. An adjusting device for yarn-moistening machines including a centrifugal brush for scattering moisture over the yarn, a belt conveyor for carrying the yarn past said centrifugal brush, an immersion roller adapted to supply moisture to said centrifugal brush, means for driving said belt conveyor, means for driving the immersion roller, a change speed gear for varying the ratio between the speed of the immersion roller and the speed of the belt conveyor, said change speed gear including a slotted positioning bar bearing

60 marks denoting the nature of the yarn, a pair of driving pulleys having curved surfaces, a

65 driving belt passing round said driving pulleys, a belt fork, slideable in the slot in the positioning bar, for shifting said belt from one mark to another, the curvature of the surfaces of the driving pulleys being such

70 that a displacement of the positioning bar ensures the same percentage increases and decreases in moistening for all the spun materials corresponding to the various marks on the positioning bar, a spindle adapted to dis-

75 place the positioning bar longitudinally, a toothed wheel mounted on said spindle, a second toothed wheel meshing with said toothed wheel, a scale applied to said second toothed wheel, a shaft on which said second toothed wheel is mounted, and a pointer at the free end of said shaft, said pointer standing in front of said scale.

80 In testimony whereof I have signed my name to this specification.

HEINRICH PFERDMENGES.
